UNITED STATES PATENT OFFICE.

JOSEPH SCHWEISS, OF ST. LOUIS, MISSOURI, ASSIGNOR TO LANDIS MACHINE COMPANY,
OF ST. LOUIS, MISSOURI, A CORPORATION OF MISSOURI.

BUTTON-STAPLING MACHINE.

1,244,135.

Specification of Letters Patent. Patented Oct. 23, 1917.

Application filed April 21, 1917. Serial No. 163,602.

To all whom it may concern:

Be it known that I, JOSEPH SCHWEISS, a citizen of the United States, residing at the city of St. Louis, State of Missouri, have invented a certain new and useful Improvement in Button-Stapling Machines, of which the following is a full, clear, and exact description, such as will enable others skilled in the art to which it appertains to make and use the same, reference being had to the accompanying drawings, forming part of this specification.

This invention relates to certain improvements in button setting machines of the type wherein a button and wire are fed into the proper association, the wire is formed into a staple in engagement with the button, and the staple carrying the button is then set and clenched in the work.

The objects of the invention are to provide a machine of this sort which by virtue of the small number and simplicity of parts required, will be economical in cost, durable in construction, easy to operate, and not subject to disorder.

Further objects reside in the provision of means enabling the rapid interchange of buttons, and the provision of new and improved mechanisms and details of construction for performing more efficiently the customary operations of machines of this type. Other and further objects will be obvious or pointed out hereinafter, reference being had to the illustrative embodiments shown in the accompanying drawings in which—

Figure 1 is a front elevation of the machine;

Fig. 2 is a side view with various parts in longitudinal section;

Fig. 3 is a part plan view with certain upper portions of the machine removed;

Fig. 4 is a detail showing certain of the parts of Fig. 3 in a different position;

Fig. 5 is an elevational view with parts in longitudinal section substantially on line 5—5 of Fig. 1.

Referring to these illustrations by the reference numerals applied, let it be understood that the numeral 1 indicates a suitable frame which is mounted on any proper support in conjunction with the conventional operating treadle. The forward portion of the frame is shaped to provide the horn or anvil 2, and the rearward portion of the frame provides a housing for certain of the working

parts, as shown in elevational section in Fig. 2. A stub shaft 4 is journaled in the frame adjacent the rear portion of the machine, and within the housing portion carries a bell crank lever 5, and on an end projecting from the housing carries the crank member 6. On a pivot member 7 on the outer wall of the housing is pivoted a second bell crank 8. For the purpose of distinction, I will designate the bell crank 5 as the forming bell crank, and the bell crank 8 as the button feeding bell crank. A crank pin 9 on the member 6 has operative engagement with one arm of the bell crank 8, while a reciprocating link 10, operably associated with the conventional treadle at its lower extremity, is connected with one arm of the forming bell crank 5. Consequently, when the link 10 is reciprocated by operation of the treadle, the bell cranks 5 and 8 will be rocked on their pivots.

Extending from the right side of the frame 1 is a table portion 11 having means arranged at its outer extremity for supporting the conventional spool of staple wire 12. Pivoted at 14 on the table portion 11 is a wire feeding arm 15, hereinafter to be described more in detail. The side walls of the frame member 1 terminate at their upper extremities as parallel inclined guiding members 16 and 16' and trackways 17 and 17'. Reciprocally mounted on these track and guide members is the former block 18 which is in the form of a bifurcated member having a cross connecting member 18a at its lower side. Reciprocally mounted on the former block and between the legs thereof is the driving member 19. The forward end of this driving member is slotted to provide the longitudinal upwardly opening slot designated by the numeral 19a. The rearward end of the driving member 19 extends beyond the rearward extremity of the former block 18, and carries a laterally projecting lug 20 and a depending portion 21. In a channel in the rear portion of the former block 18 is a plunger 22 held outwardly by a coiled spring 24. The plunger 22 lies in the path of the lug 20. Operably connecting the depending member 21 and the upwardly extending arm of the forming bell crank 5 is a link 25. The extremity of the vertically extending arm of the bell crank 5 is disposed in proximity to the former block 18, and carries a single gear 110

tooth 26 designed to have operative engagement with the former block within a notch which is provided in its lower side, as best seen in Fig. 2. By virtue of the connections just described, as the bell crank 5 is swung forwardly by the downward movement of the link 10, the tooth 26 will engage the forward side of the notch of the former block and slide the block forwardly, 10 while the driving member 19 is also carried forwardly by virtue of its connection with the bell crank 5 through link 25. The initial movement of the bell crank 5 which brings the gear tooth 26 against the forward wall 15 of the notch in the former block, also brings the lug 20 closer to the end of the plunger 22. As the former block is carried forward by the swinging movement of the bell crank 5, it ultimately reaches a point where the 20 tooth 26 will be disengaged from the notch in the block, whereupon the further movement of the block, as well as the movement of the driver, is accomplished by virtue of the engagement of the lug 20 against the 25 plunger 22, and the operative connection of the driver with the bell crank by means of link 25. In this fashion the latter portion of the movement of the former block is accomplished through the cushion connection furnished by plunger 22 and spring 30 24. When the former block reaches its limit of movement, which is determined by the thickness of the work with which it is brought into contact, the driver will continue its downward movement, which is permitted by this yielding connection afforded by spring 24. The driver is provided with lugs 13 which move in grooves 23 in the former block. On the rearward movement 35 40 of the driver, these lugs come up against the rear ends of the grooves 23 and move the former block rearwardly to the point where the notch on its lower portion is in position for engagement by the tooth 26. 45 Below the former block and in line with the driver, is disposed a mandrel 27, which is fulcrumed at 28, and has an upwardly directed front arm 29 and an upwardly directed rear arm 30. The rear arm 30 is 50 disposed in the path of the cross connecting member 18^a carried on the former block, so that the latter will ride over the arm 30, swinging it downwardly and swinging the forward end 29 of the mandrel member up 55 between the legs of the former block and into the plane of the driver. The forward lower portion of the driver is formed as a rearwardly sloping inclined plane which is adapted to engage the forward end 29 of 60 the mandrel member and cam it downwardly out of the path of the driver when the former block is moved forwardly a distance sufficient to disengage the cross connecting member 18^a from the rearward end 65 of the mandrel member.

Referring now to Fig. 3, it will be understood that the wire feeding arm 15 carries at its outer or free end a detent member 31 adapted to engage wire fed from the spool 12, so as to carry the wire as the arm swings away from the spool, which it does under the influence of a spring 32. The means for controlling the movement of the wire feeding arm 15 includes a short bearing arm 34 extending leftwardly from the wire feeding arm and carrying at its extremity an anti-friction roller 35. This roller is adapted to engage the lateral margin of the former block 18. This margin of the former block 18 is formed with an offset 36 which permits the arm 15 to swing leftwardly as the former block is retracted, and then presses the arm 15 toward the right as the former block moves downwardly. The wire thus fed leftwardly by movement of the arm 15 is held against rightward movement by the detent 37, and passes through the wire channel 38 in back of the forward end 29 of the mandrel, in which position a section is sheared off by the former block upon its downward movement, all in the customary fashion.

Referring now to Figs. 1, 2 and 5, it will be seen that a cover plate 39, screwed to the guide members 16 and 16', covers the former block and the driver, and said cover plate has a rightwardly extending portion 39^a which covers the wire-feeding arm 15. In this portion 39^a is rotatably mounted a pin 40 which carries at its upper extremity above the member 39^a a yoke 41, and at its lower extremity below the member 39^a an arm 42. This arm extends leftwardly, as best seen in Figs. 1 and 3, to a point where it is engaged by a pivoted crotch member 44 rotatably mounted on the upwardly extending arm of the button feeding bell crank 8. The table member 11 is suitably apertured to permit the passage of the upper extremity of the said bell crank member, 45 and as seen in Fig. 5 the cover portion 39^a is shaped to accommodate its forward and rearward oscillatory movement. Pivottally mounted in the yoke 41 is a button-feeding finger 45, the arrangement being such that the feeding finger may be swung downwardly into the operative position shown in full lines in Fig. 1, or upwardly into the inoperative position shown in dotted lines. A tension member 46 (see Figs. 1 and 5) 50 which is pivoted at 46^a and urged downwardly by a spring 46^b, is adapted to contact with the upper surface of the button feeding finger so as to exert a yielding pressure upon the same in a downward direction. The tension member 46 has a lower bearing edge, which engages the button feeding finger, formed with considerable length to accommodate movement of the button feeding finger. The tension mem- 55 60 65 70 75 80 85 90 95 100 105 110 115 120 125 130

ber 46 carries a lateral projection 46^c which may be engaged by the finger of the operator to lift the tension member away from the button feeding finger to enable the latter to be swung up to the position illustrated in dot and dash lines in Fig. 1. The forward extremity of the button feeding finger is deflected downwardly at an angle to its body portion to provide the button engaging portion 45^a which is suitably shaped at its lower margin to engage a button.

A button tube 47 of conventional form is removably mounted on the cover portion 39 in pedestal members 48 and 49, the upper extremities of which are slotted to receive the downwardly projecting portion of the tube which forms the button-eye receiving channel. On one of the pedestal members 20 is pivoted a latch 50 which may be swung into engagement with the tube to hold it seated in the notches aforesaid, or may be swung laterally away from the tube to permit its removal therefrom. At its 25 lower extremity the tube abuts a button guide plate 51 which first slopes downwardly from the end of the tube on a plane substantially parallel with the tube and then changes its angle of slope so as to continue 30 substantially parallel with the former block and driver, in which position it lies directly above and forms a cover for them. The button guiding plate is provided with a button slot designated by the numeral 52 35 which registers with the eye receiving channel of the tube 47 at its upper extremity, and for a portion of its length adjacent the lower portion of the plate lies in alinement with the groove 19^a of the driver. The slot 40 at the lower extremity of the tube 47 lies on a radius relative to the pin 40 equal to the length of the button feeding finger 45, and the adjacent portion of the slot 52 is also formed substantially on the same radius, so that the slot takes a rightwardly 45 slanting or arcuate direction as illustrated in Fig. 1. At the point where the slot comes into alinement with the slot 19^a of the driver, it changes its direction to the left 50 so that it leaves the said radius and lies out of the reach of the button feeding finger 45. A spring finger 54 is adapted to retain buttons in the tube 47 from sliding into the slot 52. Depending from the button feeding finger 45 and pivotally secured thereto, is an elevating pallet 55 which is formed so as to permit its oscillation rearwardly on its pivot, but not forwardly. Mounted on the cover portion 39^a in co-operative relationship with the pallet member 55, is a cam member 56 sloping upwardly 55 from its forward edge.

By virtue of this arrangement of parts, whenever the button feeding bell crank 8 is oscillated by the means heretofore described,

it will first swing rearwardly, swinging the arm 42 which in turn rotates the pin 40 and swings the button feeding finger 45 rearwardly. In the rearward movement of the button feeding finger, the pallet member 55 70 comes into contact with the cam member 56, and rides up the sloping face of the latter, thereby elevating the free extremity of the button feeding finger. In this movement, the button feeding finger is held under yielding tension by the tension member 46, which permits its upward as well as its rearward movement. When, in the course of the rearward movement of the button feeding finger, the pallet member 55 reaches the rearward 80 extremity of the cam member 56, it drops off of the same, thereby directly lowering the free extremity of the button feeding finger. This brings the button engaging portion 45^a down on top of and into operative engagement with the lowermost button which is retained by the spring finger 54, the tension member 46 operating thus to force the button feeding finger downwardly into engagement with the button. This being accomplished at the end of the rearward movement of the bell crank 8, the latter then rocks forwardly, swinging the free end of the button feeding finger forwardly through the instrumentality of the connections just described. 85 As the button feeding finger moves forwardly, it carries the button with which it is in engagement out from under the spring finger 54 and down the plate 51, the eye of the button riding in the slot 52, the pallet 55 90 being rocked rearwardly upon engagement with the cam member 56 so as to permit the extremity of the button feeding finger remaining in engagement with the button. The button is carried forward by this movement to the point where its eye comes up against the extremity of the mandrel member 29, at which point the button guiding slot changes direction, so that the further movement of the button feeding finger carries it out of the path of the button, as will be obvious from Fig. 1. The rearward tip of the member 45^a, however, is left in engagement with the button so as to steady it 95 in position to receive the staple wire. The wire is fed to the button by movement of the arm 15 in the manner above described. At the next depression of the treadle, the former block moves downwardly in the manner above described to shear off the section of the wire and to bend it about the mandrel 29 to form the staple in the customary fashion. The driver 19 then moves downwardly to engage the button and staple and carry it forward and set it in the work in the well known manner. It will be observed that by the articulation of the parts, the button feeding finger moves rearwardly as the former and driver move forwardly. The slot 19^a in the driver is formed to accommodate the eye 100

130

of the button which is brought down by the button feeding finger while the driver is moving rearwardly.

In order to prevent the feed of wire when no button is fed to the stapling position, I provide on the cover portion 39^a a stop member 58 which is spring-pressed upwardly so that its upper extremity will lie in the path of the lower face of the button feeding finger 45. When projected downwardly, the lower extremity of the stop member 58 is adapted to lie in the path of the wire feeding arm 15 where it may engage an abutment member 59. When, in the forward movement of the button feeding finger 45, the button engaging member 45^a is raised on top of a button, the arm will be held out of contact with the upper extremity of the stop member 58. Consequently, the latter will not be projected into the path of the wire feeding arm 15. If, however, no button is engaged by the button engaging portion 45^a of the button feeding finger, the latter will be permitted to drop into engagement with the upper extremity of the stop member 58, so as to press the latter downwardly into the path of the wire feeding arm 15 to effectively hold the latter against feeding operation.

From the foregoing description of the construction and operation of my device, it will be seen that it possesses very distinct advantages arising from the construction and articulation of the various parts. All cams are obviated by the arrangement whereby the movement of the mandrel and of the wire feeding arm are controlled directly by the former block. The method of actuating the former block provides a positive driving connection to effect the wire severing and forming operation, and a cushioned or yielding pressure driving connection for the block as it is carried forwardly to bring the staple into position against the work, said yieldable driving connection permitting the former to accommodate its forward movement to work of different thicknesses. The arrangement of the button feeding finger permits its being thrown entirely away from the button stapling position, to the position indicated in dot and dash lines in Fig. 1, which permits the machine to be used to staple an odd button, viz., one of a sort differing from those in the tube, without requiring the removal of the tube from the machine or the insertion of the odd button in the tube and the feeding out of the other buttons below it. The relative disposal of the button feeding finger, the tube and the forming and driving mechanism permits the button to be carried to the driving position without interference from the finger, and at the same time greatly reduces the extent of movement of the various parts of the machine.

It is to be observed further that this construction requires but very few parts, and that all of the parts may be made of such size as to secure great strength and insure certainty of operation. The working parts are all well housed and protected and the machine as a whole is very compact.

While I have described above an embodiment of the invention which I now consider the best form for the application of the principles of my invention, I am aware that my invention is not limited to this particular embodiment but that its principles may be applied in other structures differing therefrom yet comprehended within the scope of the following claims.

What I claim is:—

1. In a stapling machine, the combination of a forming block mounted for reciprocatory movement, a driver mounted in association with the forming block for reciprocatory movement differential to the movement of said block, and an actuating member having a permanent operative connection with the driver and an independent releasable operative connection with the block whereby those members may be actuated for their reciprocatory movement, there being a yielding pressure means forming an operative connection between the block and the driver whereby the block may be actuated by movement of the driver.

2. In a stapling machine, the combination of a forming block and a driver mounted for differential reciprocatory movement, an actuating lever, said lever having continuous operative connection with the driver, the lever and the forming block being provided with means forming an operative connection, said lever being operable to disengage said connection, and yielding pressure means associated with the driver and forming block to provide an operative connection for the two.

3. In a stapling machine, the combination of a reciprocatory forming block, a differentially reciprocatory driver associated therewith, an oscillatory actuating member, a portion of said actuating member being movable into and out of operative connection with the forming block upon movement of the actuating member, and a portion carried by said actuating member forming a permanent operative connection with the driver.

4. In a stapling machine, the combination of a reciprocatory forming block, a differentially reciprocatory driver, an actuating member, and means for moving the same, there being a permanent operative connection between the actuating member and the driver whereby the latter is moved upon movement of the actuating member, there being an independent operative connection between the actuating member and the form-

ing block whereby the latter is moved during only a portion of the movement of the actuating member, and there being a yielding pressure member associated with the forming block and the driver whereby the block may be moved differentially by movement of the driver.

5. In a stapling machine, the combination of a reciprocatory driving member, a reciprocatory forming member, an oscillatory actuating member, means for moving the actuating member, and a link forming a permanent operative connection between the actuating member and the driving member, the actuating member having free operative connection with the forming member.

6. In a stapling machine, the combination of an oscillatory actuating member, a reciprocatory forming member disposed tangentially to the arc of the oscillatory member and having a free operative connection therewith, and a driver member having permanent operative connection with the actuating member, there being a yielding connection 20 between the driver member and the forming member whereby the latter may be actuated from the driver independently of its own connection with the actuating member.

7. In a stapling machine, the combination of a reciprocatory forming member, a differentially reciprocatory driver, an actuating member having permanent operative connection with the driver and an independent free operative connection with the forming member whereby to permit the differential movement of said members, and a yielding pressure member forming an operative connection whereby the forming member may be moved by movement of the driver, the driver and forming member having operative connection whereby the latter may be positioned for engagement with the actuating member.

8. In a button stapling machine, the combination with suitable forming and driving mechanism, of a button container spaced apart from said mechanism, and a button feeding finger pivoted at one side of said container and said mechanism, for oscillatory movement intermediate said container and said mechanism across the line of movement of the driving mechanism.

9. In a button stapling machine, the combination of a reciprocatory driver, a button container, a guide member having a slot extending from the container to the driver, and a button feeding finger pivoted at one side of the driver for oscillatory movement to and from the container across the path of movement of the driver to move a button from the container through said slot and into the path of the driver.

10. In a button stapling machine, the combination of a reciprocatory driver, a button container disposed at one side thereof, a

slotted guide plate for guiding buttons from the container to the driver, and a button feeding finger movable across the slot in said plate to convey buttons from the container to a position in the path of the driver.

11. In a button stapling machine, the combination of a reciprocatory driver, a button container disposed at one side of the path thereof, a button feeding finger, and means for moving said finger from the container to a position at the opposite side of the path of the driver.

12. In a button stapling machine, the combination of a reciprocatory driver, a button container disposed at one side of the path thereof, a button feeding finger pivoted at the other side of the path of the driver, means for actuating said finger to convey a button laterally from the container to a position in front of the driver, and means for actuating the driver.

13. In a button stapling machine, the combination of a driver, a guide plate for sustaining a button in position to be moved by said driver, a button feeding finger pivoted at one side of said plate, and a tension member for retaining said finger in engagement with a button on the plate, said tension member and said finger having mountings permitting the fingers being swung free from the tension member and away from the plate.

14. In a button stapling machine, the combination of a staple forming mechanism, a button supporting plate, arranged to support a button to receive a staple from said mechanism, an oscillatory button feeding finger movable on an axis substantially perpendicular to said plate and adapted to convey buttons to said plate, said finger being mounted for movement also on an axis extending at an angle to said first mentioned axis, and a tension member co-operating with said finger to urge it toward said plate.

15. In a button stapling machine, the combination of staple forming mechanism, a plate for supporting a button for co-operation with said mechanism, a button container disposed above and to one side of said plate, a button feeding finger mounted at one side of said plate for movement on two axes, and means for moving said finger on said axes to convey a button from said container to said plate.

16. In a button stapling machine, the combination, with staple forming mechanism, of a button supporting plate for supporting a button for co-operation therewith, a button container, and a button feeding finger pivoted at one end for oscillation in different arcs and comprehending said container and plate in its scope of movement.

17. In a button stapling machine, the combination of a button feeding finger, a pivoted member upon which said button feed-

6
ing finger is mounted for oscillatory movement, said pivoted member being movable to swing the feeding finger in a different direction, a button container, staple forming mechanism, a button sustaining plate for holding a button for coöperation with said mechanism, means for guiding said finger into operative association with said container and said plate, and tension means for 5 pressing said finger into coöperation with said container and said plate.

18. In a button stapling machine, the combination of a button container, a wire-feeding device, a button sustaining plate for supporting a button to the operation of said wire-feeding device, a button feeding finger arranged to coöperate with the plate to hold a button, a universal mounting for said button feeding finger, means for actuating said 15 button feeding finger through said mounting, and means for guiding said button feeding finger into operative association with the container and the plate.

19. In a button stapling machine, the combination of a wire-feeding device, a button container, a button sustaining plate, a button feeding finger adapted to coöperate with the plate to hold a button to the 25 operation of the wire feeding device, a universal mounting for said button feeding finger, means for actuating said finger through said mounting, and yielding pressure means coöoperating with said finger to urge it toward said container and said 30 plate.

20. In a button stapling machine, the combination of a wire feeding arm pivoted for oscillatory movement, a button feeding finger pivoted for oscillatory movement and 35 extending across the said arm, and a stop device operable by the finger to prevent movement of the arm.

21. In a button stapling machine, the combination of a frame member, a wire feeding arm pivoted for oscillatory movement

thereon, a cover plate mounted on the frame to cover the arm, a button feeding finger pivoted on the cover plate, and a stop member mounted on the cover plate in operative association with the finger and the arm.

50

22. In a button stapling machine, the combination of a frame, a wire feeding arm mounted for movement thereon, a button feeding finger having a universal mounting on said frame, a stop member operable by 55 said finger to engage the arm, and a yielding pressure means coöoperating with said finger to urge it for effective coöperation with said stop member.

23. In a button stapling machine, the combination of a button container, a button sustaining plate, a wire feeding arm, a stop member associated with said arm, a universal mounting for said feeding finger, and yielding pressure means for urging said 60 finger into operative association with the container, the plate and the stop member.

24. In a button stapling machine, the combination of stapling mechanism, a button sustaining plate for holding a button to the 70 operation of said mechanism, a button feeding finger, tension means for urging said finger for operative association with the plate, and a universal mounting for said finger whereby it may be moved out of co-operation with said tension means and said 75 plate.

25. In a button stapling machine, the combination of stapling mechanism, a button container, a button feeding finger for 80 conveying a button from said container to said mechanism, tension means for urging said finger for coöperation with the container, and a universal mounting for the finger whereby it may be moved out of association with the tension means.

In testimony whereof I hereunto affix my signature this 19th day of April, 1917.

JOSEPH SCHWEISS.
